CLAIM

I claim the ornamental design for an applicator device, as shown and described.

DESCRIPTION

FIG. 1 is a front perspective view of an applicator device; FIG. 2 is a side elevation view of the applicator device shown in FIG. 1;

FIG. 3 is a front elevation view of the applicator device shown in FIG. 1;

FIG. 4 is a rear elevation view of the applicator device shown in FIG. 1; and,

FIG. 5 is a top view of the applicator device shown in FIG. 1.

The claim ends along the edges defined by the surface shading on the distal end of the neck and the flattened free end of the handle. The broken lines immediately adjacent the surface shading represent the bounds of the claimed design and all of the other broken lines are for illustrative purposes only. None of the broken lines form part of the claimed design.
